FURNITURE ARM OR SIMILAR ARTICLE

Burton H. Kaplan, Potomac, Md., assignor to Rowe Furniture Corporation

Filed Sept. 30, 1974, Ser. No. 510,584

Term of patent 14 years

Int. Cl. D6—06

U.S. Cl. D6—194

FIG. 1 is a front perspective view of a furniture arm or similar article showing my design;

FIG. 2 is a view in side elevation on a larger scale; and

FIG. 3 is an enlarged fragmentary view taken along sight line 3—3 of FIG. 1 and showing one of the identical ornamental plaques in greater detail.

I claim:

The ornamental design for a furniture arm or similar article, substantially as shown.
